CURLER

William Finkelstein, Bronx, N. Y.

Application October 17, 1940, Serial No. 361,473

3 Claims. (Cl. 132—41)

My invention relates to a new and improved curler which can be manufactured and assembled at low cost and which can be used in a simple and convenient manner.

One of the objects of the invention is to provide a curler which has a curling rod, a clamping bar pivoted to said curling rod, and a retaining member which can be detachably connected to the outer end of the curling rod.

Other objects of my invention will be set forth in the following description and drawing which illustrates a preferred embodiment of the invention, it being understood that the above statement of the objects of my invention is intended generally to explain the same and without limiting it in any manner.

Fig. 1 is a top plan view of the improved device.

Fig. 2 is a bottom plan view of the improved device.

Fig. 3 is a sectional view on the line 3—3 of Fig. 1.

Fig. 4 is a sectional view on the line 4—4 of Fig. 3.

Fig. 5 is a sectional view on the line 5—5 of Fig. 3.

Fig. 6 is a plan view of another type of supplemental clamping member.

The hollow curling rod 1 is made of any suitable material. This material is preferably a plastic material, such as cellulose acetate or the like, which can be readily molded into the desired shape. The outer end of the curling rod 1 is closed, as clearly shown in Fig. 3. This curling rod may be provided with two series of perforations 2. The curling rod 1 is of substantially cylindrical shape and it is provided with a thickened or reinforced rear extension 1a. Said extension 1a is of general half-round shape, in lateral cross-section. A clamping rod 3, which can be made of any suitable metal, is pivotally connected to the curling rod 1. A blade spring 4, which is made of any suitable metal, has its legs located between the rear end-portion of the pivoted rod 3 and the extension 1a, so that the clamping rod 3 is normally held in the clamping position which is shown in Fig. 3.

A supplemental resilient clamping member C, which is made of any suitable metal, is provided with legs 5 and 6 which are bent so as to provide a pair of front loops 7 and 7a. The front loops 7 and 7a are integral with the legs 5 and 6, and said front loops are formed by helically bending the legs 5 and 6 at the front end of the supplemental clamping member C.

The inner ends of the legs 5 and 6 are bent to form pivot portions 5a and 6a, which pass

through laterally opposed bores in the reinforced rear end-portion 1a of the curling rod 1. Said pivot portions have parts which are located in extension 1a and which are forwardly bent. 5 The inner end of the pivoted clamping rod 3 is provided with integral perforated lugs L, through whose perforations said pivot portions 5a and 6a are also passed, in order to provide a pivotal connection for the clamping rod 3. The outer wall of the extension 1a is non-circular or polygonal, and its inner wall is substantially semi-cylindrical. The pivot portions 5a and 6a are located in front of the legs 4 of the spring, as shown in Fig. 5. As shown in Fig. 4, the outer periphery of extension 1a has opposed planar faces, which are abutted by respective planar faces of the inner walls of lugs L.

The closed tip of the curling rod 1 is provided with a groove with which the loops 7 and 7a can be releasably interlocked by longitudinally extending the arched and resilient legs 5 and 6, so that the resilience of said legs maintains said loops 7 and 7a detachably engaged with this groove.

20 The device is used in the well-known manner, by clamping the end of a strand of hair between the curling rod 1 and the clamping bar 3, while the front end of the clamping member C is disengaged from the curling rod 1. The device is then turned in order to wind the lock of hair helically or spirally around the members 1 and 3, and the loops 7 and 7a are then engaged with the groove at the closed tip of the member 1.

25 The clamping member C' which is shown in Fig. 6, has shoulders 10 which abut each other, and which are integral with a loop 1b, which is normally closed. The member C' is made of resilient wire. The shoulders 10 releasably lock with the transverse groove at the tip of the curling rod.

30 It is unnecessary to connect the extension 1a to the respective leg of spring 4, because the metal rod 3 is connected by a rivet or the like to the respective leg of spring 4.

35 It is obvious that the device can be manufactured and assembled at low cost. In the preferred embodiment, the front tip of the curling rod 1 is imperforate. However, the invention is not restricted to this. For the purposes of the claims, a curling rod which has a closed tip is defined as a curling rod whose outer end has a lateral end-portion which provides a groove which can be releasably engaged by the outer end of the clamping member C.

40 I have shown a preferred embodiment of my invention, but it is clear that numerous changes

and omissions can be made without departing from its spirit.

I claim:

1. A curling device having a curling rod, a clamping rod which has lateral lugs, a clamping member, said clamping member having arched resilient longitudinal legs and being closed at the outer end thereof, the front end of said curling rod having an external lateral groove, the outer end of the clamping member being shaped to releasably interlock with said groove when said arched resilient legs are longitudinally extended, said legs having pivot portions which pass through transverse bores of said curling rod and through transverse bores of the lugs of the clamping rod in order to pivotally connect the clamping rod and said clamping member to said curling rod, said pivot portions having parts which are located in said curling rod and which are forwardly bent and which are unconnected to each other, a blade spring connected only to said clamping rod and having a spring-leg which abuts the adjacent portion of said curling rod, said blade spring being adapted to hold the pivoted clamping rod in clamping position, the inner ends of said pivot portions being located in front of said blade spring.

2. A curling device comprising a curling rod which has a lateral groove in the front end thereof, a clamping rod, spring means normally holding said clamping rod in clamping position, a clamping member which has longitudinally arched and resilient legs which are pivotally connected to said curling rod rearwardly of the front end of said curling rod, the front ends of said

legs having integral loop-shaped means which are adapted to detachably engage said groove, said legs being pivotally connected to said curling rod by lateral pivot extensions of said legs which pass through bores of said curling rod and also through the perforations of lugs of said clamping rod into said curling rod so that said pivot extensions turnably connect said clamping rod to said curling rod, the portions of said pivot extensions which are located in said curling rod being unconnected from each other and being forwardly inclined.

3. A curling device comprising a curling rod whose front tip is closed, said tip having a transverse groove, the rear end of said curling rod having a hollow extension, a clamping rod having pivot lugs, a clamping member which has resilient longitudinal arched legs, the inner ends of said legs being bent laterally and passing through bores in said lugs and through corresponding bores in the wall of said extension in order to pivotally connect said lugs and said legs to the wall of said extension, said clamping member having a closed outer end which is shaped to releasably engage said groove, a bent blade spring having a pair of spring legs, said blade spring being located rearward of the legs of the clamping member, one of said spring legs being connected to the adjacent portion of the pivoted clamping rod, the other spring leg abutting the inner wall of said extension, the parts of the laterally bent portions of said legs which are located in said hollow extension being forwardly inclined.

WILLIAM FINKELSTEIN.
